MEANS FOR PACKAGING AND FORMING WEATHER-STRIP MATERIAL

Benjamin J. Long, Lakewood, Ohio, assignor to
B. Joel Long, Niagara Falls, N. Y.

Application February 28, 1933, Serial No. 659,018
2 Claims. (Cl. 153—10)

This invention relates to means for packaging weather-strip material and forming therefrom weather strip by drawing same from the package.

5 Another object of the invention is to provide means of the above character, which is simple and inexpensive to manufacture, convenient for the distribution of weather strip, and easily manipulated for obtaining a desired length of
10 weather strip.

With the above and other objects in view, the invention will be hereinafter fully described as illustrated in the accompanying drawing, and the novel features thereof will be distinctly
15 pointed out in the appended claims.

In the drawing, similar characters of reference are used to designate corresponding parts.

Figure 1 is a perspective view of a box or package constructed in accordance with my invention.

Fig. 2 is a fragmental portion of the box, on an enlarged scale, illustrating the recess in the side thereof.

Fig. 3 is a perspective view illustrating a portion of a weather-strip material.

Fig. 4 is a similar view after the weather-strip material has been drawn through the die and from the box,

Fig. 5 is a plan view of the box with the coil of weather-strip material therein packed for distribution,

Fig. 6 is a similar view, or end of the weather-strip material passing through the recess in the side of the box for being drawn therefrom, and

Fig. 7 is a perspective view of the die-plate.

It is desirable to market weather strip of the flexible type in rolls, but this is not practical for the weather strip being curved in cross section cannot be rolled up without becoming kinked and thereby destroying its trueness. This invention provides means whereby, the weather-strip may be sold in a roll packed in a box, and the cross-section curve formed as the strip is drawn from the box thereby leaving it true for use. The invention will now be described:

Referring to the drawing, 1 represents a box having upstanding sides 2, and 3 a lid or cover therefor having downwardly extending flanges 4 of the same depth as the height of said sides, which box and cover may be of rectangular form and preferably constructed of cardboard or other suitable material. The weather-strip material may be of any design as for instance that indicated by 5 with longitudinally extending stiffening ridges 6 and 7, between which

nail holes 8 are provided at suitable intervals. The weather-strip material 5 is flat or substantially straight in cross section and may be rolled up as at 9 and placed in the box. Before the weather-strip material 5 is practical as weather strip, it is necessary to curve it in cross section as illustrated at 10. For curving the weather-strip material in cross section as it is drawn from the box, a die plate 11 is provided. Said die plate is provided with a suitably curved slot 12 for receiving the weather-strip material 5 and give the proper curve thereto as it is drawn through the die plate. The die plate 11 has rearwardly extending upper and lower flanges 13 and 14 and is of the same height as the depth of the box so that it will be held in position between the bottom of the box and the top of the cover, when a person holds the cover down with his left hand and draws the strip through the die by pulling with his right hand. The side of the box 2 and the flange 4 of the cover 3 near a corner thereof, are provided with corresponding vertical recesses 16 and 17 for permitting the withdrawing of the weather strip from the box.

In practice, the weather-strip material in the form of a roll is placed in the box 1, the free end 18 thereof being inserted through the curved slot 12 of the die plate 11. The weather-strip material is thus packed convenient for distribution. When the purchaser or user desires to obtain a piece of weather strip of any desired length, he removes the cover 3 from the box, passes the free end 18 of the weather-strip material 5 through the recess 16, replaces the cover and holds it down with his left hand, and then pulls upon said free end of the weather-strip material until the required length is obtained and may be cut from the roll. The pulling upon the weather-strip material causes the die plate 10 to engage the upright side 2 of the box. Thus the weather-strip material in a roll is packed in a box for convenient distribution and curved in cross section ready for use when withdrawn from the box.

From the drawing and description, it is clear that the invention will accomplish the intended purpose, and it is to be understood that slight changes in the details of construction may be made within the scope of the claims.

Having fully described my invention, what I claim is:

1. In a means for packaging and forming weather strip, the combination of a box adapted to hold a roll of weather-strip material, the box

- having upright sides, a side of the box having a recess, a cover for the box, the cover having an opening adapted to register with said recess, a die-plate, the die-plate having flanges adapted 5 to engage said box and cover, and the free end of said roll of weather-strip material passing through said die-plate and being adapted to be drawn therethrough and through said recess of the box and opening of the cover.
- 10 2. In a means for packaging and forming weather strip material, the combination of a box adapted to hold a roll of weather strip material, the box having a recess through the side thereof, a cover for the box, the cover having an opening adapted to register with the recess of the box for permitting the withdrawal of the weather strip material from the box, a die-plate, the die-plate being adapted to receive 5 the free end of said roll of weather strip material and be enclosed in said box, and the free end of said roll of weather strip material being adapted to be drawn through said die-plate for forming same and out through said recess 10 and opening.

BENJAMIN J. LONG.
